UNITED STATES PATENT OFFICE.

ALBERT BENSON, OF MELROSE, MASSACHUSETTS.

GAME-BOARD.

SPECIFICATION forming part of Letters Patent No. 243,194, dated June 21, 1881.

Application filed April 27, 1881. (No model.)

To all whom it may concern:

Be it known that I, ALBERT BENSON, of Melrose, Middlesex county, Massachusetts, have invented a new and Improved Game-Board, of which the following is a specification.

The object of my invention is to produce a new and improved game-board for playing with marbles.

The invention consists in a circular board 10 slightly inclined toward the middle and provided in its upper surface with a series of concentric circular grooves. A series of grooved radial arms, with baskets or boxes at the outer ends, are provided at the inner ends with tenons 15 fitting in mortises in the edge of the circular board, which is provided with a sliding tally-strip adjoining each radial arm.

In the accompanying drawings, Figure 1 is a plan view of my improved game-board. Fig. 20 2 is a sectional elevation of the same. Fig. 3 is an elevation of the inner end of one of the radial arms, and Fig. 4 is an elevation of a part of the edge of the board and of the sliding tally-strip.

25 Similar letters of reference indicate corresponding parts.

The circular board A is slightly inclined from the edge toward the middle, and is provided with a series of circular concentric 30 grooves, B, and a central recess, B', in the upper surface. The center of this plate is marked 13, and the rings or grooves B are marked 12 11, &c., toward the turned-up edge C of the board. The edge of the board A is provided 35 with a series of mortises, D, to receive the tenons E' of a series of arms, E, provided with a groove, J, in the upper surface, and with a basket or box, F, at the opposite end. The turned-up part of the edge C is provided with 40 a recess, G, above each mortise D, this recess corresponding in form and size with the groove J in the upper surface of the arms E. A graduated and numbered tally-strip, H, is held to the edge of the board A by means of a pin or 45 button, L, passing through a longitudinal slot in this strip and into the edge of the board A, thus permitting this strip to be moved up and down vertically, so that the number of points scored will be visible on this strip.

The game is played as follows: Marbles are 50 placed in the baskets or boxes F, the marbles in each basket having a different color, which is the same as that of the corresponding tally-strip. The player shoots the marbles from the basket F through the groove J, and as the 55 marble crosses the board A it remains in one of the grooves B or in the recess B', the player counting the number of the ring on which his marble rests in his favor.

The sliding tally-strip is preferably provided 60 with a spring on its inner side, which spring presses it outward against the head of the screw or pin L, whereby the strip will be held at any desired height.

The board A and the arms E are preferably 65 provided with short legs.

Having thus described my invention, I claim as new and desire to secure by Letters Patent—

1. A game-board made substantially as herein shown and described, and consisting of a 70 circular board, A, with concentric grooves B in its upper surface, combined with a series of grooved radial arms, as set forth.

2. In a game-board, the combination, with the circular board A, having concentric grooves 75 B in its upper surface, of the grooved radial arms E, and of the baskets or boxes F at the ends of these arms E, substantially as herein shown and described, and for the purpose set forth.

3. In a game-board, the combination, with the circular board A, provided with concentric grooves B in its upper surface, of the radial grooved arms E E, and of the sliding tally-strips H, substantially as herein shown and 85 described, and for the purpose set forth.

4. In a game-board, the combination, with the circular board A, provided with mortises D D in the edge, of a series of grooved arms, E, provided with tenons E' fitting in the mortises D, substantially as herein shown and 90 described, and for the purpose set forth.

ALBERT BENSON.
